UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR PIN.

Original application filed May 12, 1920, Serial No. 380,826. Divided and this application filed September 4, 1925. Serial No. 54,430.

This invention relates to pins for supporting insulators for various electrical conductors, and has for its object the provision of a device which shall be of improved construction and operation, and which shall be economical to manufacture and provide efficient distribution of the material without interfering with the electrical properties of the insulator.

10 The invention is exemplified in the combination and arrangement of parts shown in the accompanying drawing and described in the following specification, and it is more particularly pointed out in the appended claims.

In the drawing—

Fig. 1 is an elevation of a pin showing one embodiment of the present invention with the separately formed base in section;

20 Fig. 2 is a horizontal section on line 2—2 of Fig. 1.

This application is a division of application, Serial No. 380,826, filed May 12, 1920.

25 Insulators for electrical conductors are supported in a variety of ways, one of the common means being by the use of pins carried by the supporting structure and bearing the insulator fitted over the end thereof. Such pins are used for supporting insulators, 30 on metal and wooden arms and pole tops and also on various constructions other than regular line wire supports. A pin to meet the requirements to which it is subjected must have the necessary mechanical strength to withstand the stresses brought upon it and should not materially lower the flashover voltage of the insulator or otherwise diminish the electrical efficiency of the insulator. The cost of manufacture should be 35 kept as low as possible and the pin should provide the required strength without setting up undue stress in the fragile material of the insulator which it carries. The pin should also be adaptable to various conditions which arise in line construction and other electrical installations where insulators are used, and it is also desirable that the pins should be so designed that a large variety can be made from as small a variety of stock 40 as possible.

From the embodiment of the invention shown in the drawing, it will be apparent that the small body diameter of pins constructed in accordance with this invention permits developing the maximum flashover voltage value of the insulator since the small diameter of the pin body keeps the outer surface of the body at a maximum distance from the lower edge of the insulator itself. 55 It will also be seen that the supporting base and the body portion of the insulator pin are made in separate parts which permits the use of a base having sufficient area so that the cross-arm upon which the base rests will not be crushed under bending moment. The 60 construction permits of a balanced arrangement and at the same time does not sacrifice the electrical properties of the insulator. In pins having a small base formed integral 65 with the pin, the bending moment upon the pin forces the edge of the base into contact with the upper face of the supporting structure so that where the structure is made of wood, the fibres are crushed at the edge of the base, permitting the pin to lean to one side and loosening the connection with the support. It is impractical to form a pin with an integral base of sufficient area to overcome this difficulty, for the reason that if the pin is cut from a piece of stock of large 70 diameter the waste is too great to justify a sufficient expanse of base, and if it is undertaken to upset or swage a smaller piece of stock to form the base, it is impossible to 75 expand the material a sufficient amount to 80 give a base of the required extent. Such operation also tends to form laps or flaws in the metal. Where the base is formed separately from the pin and is provided with 85 means to hold the two rigidly together, when the pin is installed, the base may be made of any desired extent and shape and pins may be standardized so that the same pins may be used with a large variety of supporting 90 bases. A pin may be secured to the base by 95 means of a tapered end fitting in a tapered socket and the taper may be so proportioned that the pins may be readily made with a swaging-machine from straight-bar stock without the loss of material. No finishing 100

operation is necessary other than the swaging process in order to obtain a good fit for the base. The taper should be such that the pin will not tend to lift out of the base 5 when a bending moment is applied, and at the same time the taper should preferably be such that the pin will not bend in the small sections, the smaller portion of the pin being reinforced by the base. When the 10 base and body are assembled they are held together so that they will work as a unitary structure and the main body of the pin may be made in straight section or given a taper which will give uniform strength for the 15 bending moment, or it may be made in stepped diameters, if desired.

The insulator may be secured to the pin in a large variety of ways, depending upon 20 conditions. In some cases a lead tip may be cast or pressed on the pin which will 25 form a cushion between the hard metal and the porcelain. The upper portion of the pin may, under some conditions, be provided with a roughened surface, or with resilient flanges or projections, to reduce the 30 danger of cracking the insulator under expansion and contraction of temperature changes. Another method of securing the insulator to the top of the pin is to provide 35 the end of the pin with large or small threads which can be adapted to a thimble of sheet material threaded into the insulator. In this construction the threaded parts may be cone-shaped and the insulator may be 40 tightened down firmly and afterwards the wire groove in the insulator may be properly alined by turning the pin relative to its supporting base. The thimbles, however, 45 instead of being cone-shaped may be cylindrical so that they can be turned upon the pins to aline the wire grooves without loosening the insulator on the pin. Where this 50 arrangement is made, the pin can be rigidly attached to the supporting base. Under most conditions, however, the pin and base will be separable which will permit combinations of various forms of pin with different kinds of bases so that the proper arrangement may be secured for a large variety of conditions.

In the form of the invention shown in the drawing, the numeral 1 designates the elongated body portion of a pin which may be formed from stock material by swaging or 55 forging to produce the elongated tapered body portion of the pin and a tapered lower end, indicated at 2 in the drawing. Below the tapered portion 2 there is provided a cylindrical extension 3 of reduced size being 60 threaded at its lower end for receiving a nut 4 which engages a washer 5 disposed beneath the cross-arm or supporting structure. The pin is provided with a base member 6 having a conical-shaped socket which is cut 65 away, as shown at 7, to provide ribs 8 for

engaging the tapered portion 2 of the pin. This enables the socket member to grip the pin and hold it more firmly against rotation. It also makes it possible to easily fit the individual pins and sockets where necessary. 70 If when the parts are assembled there is found any irregularity a drift tool may be driven into the tapered socket to bring the socket to proper taper, or the socket may be easily reamed to true shape. 75

I claim:—

1. The combination with an insulator pin, of a base for supporting said pin, said base having a socket for receiving said pin, the wall of said socket being recessed to provide 80 contact between said socket and pin for a portion only of the surface of said pin while the portion of said pin disposed in said socket has a continuously curved circular 85 outer surface.

2. The combination with an insulator pin, of a separately formed base having a socket for receiving said pin, said socket having longitudinally extending narrow ribs on the inner face thereof for engaging the surface 90 of said pin, said ribs being of less than 90 degrees extent circumferentially of said socket. 95

3. The combination with an insulator pin, of a base having a socket for receiving the lower end of said pin, said pin being enlarged at the upper end of said socket to limit the movement of said pin into said socket, and an extension on said pin below 100 said socket for attaching said pin to a supporting structure, said socket having more than two longitudinally extending narrow ribs for engaging the surface of said pin. 105

4. An insulator support comprising a pin having an elongated body member, and a 110 tapered portion at the lower end of said body member, and a separately formed base for said pin, said base having a tapered socket provided with more than two longitudinally 115 extending inwardly projecting narrow ribs each of less than 90 degrees extent circumferentially for engaging the tapered portion 120 of said pin.

5. An insulator support comprising a pin having an elongated body member, a tapered portion at the lower end of said body member, and a cylindrical extension below said tapered portion, and a separately formed base having a tapered socket provided with more than two inwardly projecting longitudinally 125 extending narrow ribs for engaging the tapered portion of said pin, said ribs being of less than 90 degrees extent circumferentially of said socket.

6. An insulator support comprising a pin 130 having an elongated tapered body portion, a relatively shorter oppositely tapered base portion, and a downwardly extending cylindrical extension below said base portion, a separately formed base having a tapered 135

socket provided with more than two inwardly projecting longitudinally extending narrow ribs of less than 90 degrees extent circumferentially of said socket for engaging the tapered base portion of said pin, and a threaded member on said cylindrical extension for drawing said pin into the tapered

socket of said base member and for clamping said pin and base member on a supporting structure.

10

In testimony whereof I have signed my name to this specification on this 26th day of Aug., A. D. 1925.

ARTHUR O. AUSTIN.
